ELECTRICAL CONNECTOR PLUG

James Edwin Wilson, Dayton, Ohio

Application August 27, 1946, Serial No. 693,185

1 Claim. (Cl. 173—361)

(Granted under the act of March 3, 1883, as
amended April 30, 1928; 370 O. G. 757)**1**

The invention described herein may be manufactured and used by or for the Government for governmental purposes, without the payment to me of any royalty thereon.

The invention to be hereinafter described relates to conductor connections.

The objectionable features and effects from the use of the conventional telephone plug for telephone switch boards and for other uses are well known, and in order to overcome some of the principal objections improved plugs have been devised in which the cord is led from the plug by a connection at right angles to the axis of the coaxial connectors.

The advantages of the last-mentioned type of plug in economizing space, minimizing deterioration of the cord where it enters the plug and beyond, lessening liability of the plug being drawn from or loosened in the socket by the weight of the cord, and otherwise, are well understood.

It is a purpose of the present invention to offer a new and novel construction in a coaxial connector plug with right angle cord outlet, which will be economical to manufacture; which will be very small in size, yet amply effective in insulation of conductors; the connections to which may be made readily and quickly by the service man or even a novice telephone user, in conventional ways. It is an advantage of the invention that it enables the making of soldered or binding screw connections in a very small plug base, with ample room for wire slack to minimize liability of breakage or loosening of such connections.

In order to more clearly disclose the construction, operation and use of the invention, reference should be had to the accompanying drawings forming part of the present application. Throughout the several figures of the drawings like reference characters designate the same parts in the different views.

In the drawings:

Fig. 1 is a side elevation of the invention, partly broken away;

Fig. 2 is a right hand elevation of Fig. 1;

Fig. 3 is a central, longitudinal cross section on line 3—3 of Fig. 2, with the removable cap member omitted;

Fig. 4 is a right hand elevation corresponding to Fig. 3;

Fig. 5 is a bottom view of Fig. 4; and

Fig. 6 is a cross section through the chambered part of cap 3, on line 6—6 of Fig. 2.

Referring to the drawings in detail, the plug

element proper of the invention comprises the usual center conducting rod or pin 1 terminating in the outer contacting tip 2. Concentric with and spaced from rod 1 is the outer conducting sleeve 3. The outer and inner conductors 3 and 1, respectively, are spaced apart and electrically separated by an intervening sleeve 4 of insulation. These three parts, collectively, constitute a plug proper. The butt end of the plug proper, which includes the input or cable ends of conductors 1 and 3 are integrally embedded in the thin planiform base half 5 of a cable gripping or clamping case disposed with its major plane at right angles to the longitudinal axis of conductors 1 and 3 (assembled). The case is also elongated in this plane, extending much farther from the plug in one direction than in the other along the axis of the cord inlet 13 later described herein. The rod 1 is headed at 16 on its base end and threaded at its outer end, and the tip 2 is internally threaded and screwed thereonto and against a "dead" section 17 of the plug consisting of an enlarged cylindrical part of the insulation 4 of the same diameter as, and set against the outer end of the sleeve 3. This insulation 4 is formed in two sleeve parts which are shown as lapped intermediate of the length of the rod 1 (although this continuity is not essential), and the inner end portion is flanged at 18 adjacent the head 16. A contact washer 19 is engaged around the rod 1 and clamped between the flange 18 and head 16. This washer has a prong 20 extended a distance in the plane of the washer and then bent at right angles and extended through the planiform face of the base opposite the plug to constitute the terminal or binding post 6 before mentioned. The base of the sleeve 3 is set against a similar larger contact washer 21 set around the insulation 4 and clamped between the sleeve and flange 18. This washer has a short prong 22 extended diametrically opposite the prong 20 and at a proper distance bent at right angles to form a second terminal or binding post 7, parallel to terminal 6 and extending through the same face of the base. The tip, sleeve contact 3, insulation 4, and the washers 19 and 21 thus comprise a unit assembly which is rigidly held together by the engagement of the tip and stem. In production the base of the sleeve 3 is set in and through one side of the mold for the base 5, the terminals 6 and 7 extend through the far side of the mold, and the base body is moulded around the parts, so that the prongs 20 and 22 are permanently enclosed and locked within the body of the base

5. In the molding, one end of the body 5 is formed with a thick block 23 of uniform thickness defining the thickness and width of the base 5, and at the opposite end portion a similarly thickened end portion 24 is formed, separated from the block 23 by a transverse recess 25 spaced sufficiently from the washers and head 18, with rounded salients and a sloping side 26 extending close to the posts 6 and 7. The completed base thus has only the conventional coaxial two-contact plug showing on the outer flat side near one end, and at the opposite inner side only two short terminals 6 and 7 project from the flat surface of the block 23. The cap 8 is deeply recessed over the block 23 and recess 25, so as to form the chamber 15. The short end of the case may be semicircular in plan as at the upper end of Fig. 2, but the opposite or inlet end is rectangular. Any one of a large number of well known insulating plastics may be used for base 5. In order to readily connect a cooperating or cap member 3, of similar plastic material to the base member 5, internally threaded metal nut cups or sockets 9 are embedded in the base 5 at time of molding exposed at the inner face of the base. Cap member 8—of the same outline as base 1 and adapted to fit flush thereon—is provided with screw-head recesses 10 in its outer surface and bores 11 concentric therewith and leading therefrom aligned with the threaded bores in cups 9. Headed clamping screws 12 passed through 11 are threaded into 9 to connect 5 and 8. When turned in tight they clamp the two parts tightly together, and also lock to the case the sheathed end portion of a conventional two-wire cord or cable, as will appear. When turned out or unscrewed sufficiently they unclamp the members and permit complete removal of the cap 8, and allow inspection of, or work on, conventional wire connections exposed on the base.

Base 5 and cap 8 are thickened at the inlet ends and formed with cooperating, complementary, circumferentially ribbed, semi-cylindrical opposed bore parts 13 having circumscribing longitudinally inclined and inwardly directed biting or anchoring ribs 14. As will be seen on reference to Figs. 3 and 4, in assembled relation, constitute a cord inlet extending inwardly to the chamber 15 in the cap and the recess 25 in the base 5, communicating with binding posts 6 and 7. The cap 8 is made as a shell chambered as at 15 so that contacts 6 and 7 extends freely therewith into with ample clearance for slack in insulated conductors extended beyond the conventional woven or other protective sheath of a conductor cord or cable when the device is completely assembled, as will be readily understood. As will be clear, a telephone plug cord or cable end clamped in bores 13 will be in position to have its conductors connected to the binding posts 6 and 7, selectively, since the bores are coaxial with the major dimension of the base, and in its longer end portion.

In using the invention, the desired cable end, with its conductor ends connected to the binder posts 6 and 7 is pressed into the semi-cylindrical portion of bore 13 of the base 5 and the cap 8 is then positioned and clamped in position by screws 12. As those screws are drawn tight, the ribs 14 on both base and cap bit firmly into the cable, anchoring it securely to the connector. Since constant movement of cables where they enter the bore or opening 13 will ultimately chafe

the braid or insulation and tend to permit the cable to pull against the connections at the binding posts 5 and 6, it is of advantage that the recess 25 is adapted to receive a knot, as customarily formed in insulated wires where practicable in conventional plugs to cushion stresses and strains applied to lead in wires of fixtures and plugs. In this case the knot will form a bearing against the end face of the case around the opening 13, and prevent external tension on the cable from being communicated to the wire at the binding post connections. With the device thus assembled, it may be plugged in the usual manner, the length of parts 1 and 3 being such that they are completely received within the cooperating jack and panel ferrule, and when the latter is countersunk the base 5 lies flush with or flat against the panel, wall, box or other surface in which the plug-in connection is made. The cable or cord, clamped between base 5 and cap 8 and securely anchored by ribs 14, may hang pendant at right angles to the plug 1 and 3, parallel with and approximately on the surface of the panel, wall, etc., free of all loops, sharp bends etc., and subject to the least possible damage by vibration. When inserted in a floor outlet, the cord will lie flat against the floor.

Such a construction and disposition of parts 30 is of particular value in use in air planes in which the space is frequently too limited or restricted to permit the plug-in connection known and used prior to this invention.

By this invention, all parts are immediately 35 ready for use. It is only necessary to connect the cable conductors in usual and well known manner to the binder posts 6 and 7 and clamp cap 8 in place by screws 12. The device is then ready to plug in.

40 Changes may be made in the construction, arrangement and disposition of the several parts of the invention within the scope of the appended claim without departing from the invention.

45 Having thus described my invention, what I claim and desire to protect by Letters Patent is:

In a telephone type plug, the combination: a 50 generally flat thin base of moulded insulating material, a plug proper extending from the principal outer face thereof normal to the major plane of the base, so that the whole has a T-shape, said plug proper comprising coaxial conductors having respective mutually spaced conductor butts and washers permanently cast within the material of the base, a cover on the base opposite the plug proper and constituting with the base a case, a cord opening formed in the 55 case radial to the axis of the plug proper and conductor-connecting terminals for each washer; characterized by said case being extended full width toward said cord opening from the plug proper, a transverse deep knot-holding recess being formed immediately inward of and wider than said cord opening, the base having a major thickened planiform end portion around the plug proper with parallel planiform inner and outer faces normal to said axis and extending flush 60 to the opposite lateral edges of the base, respective said terminals being formed on the washers extended parallel to and between said parallel faces then rectilinearly at right angles within the material of the base to and through and beyond the said inner face as short stubs spaced

widely within the area of said major thickened end portion free for access from all sides, said cover being a thin planiform member fitted to the base and chambered around said terminals and over said transverse recess, said base and cover having coextensive opposed thickened extreme end parts formed with registered parts of said cord opening.

JAMES EDWIN WILSON.
